UNITED STATES PATENT OFFICE.

JOHN R. McCONNELL, OF EMMETT, IDAHO.

SHOCK-ABSORBER.

1,084,353.

Specification of Letters Patent. Patented Jan. 13, 1914.

Application filed September 30, 1912. Serial No. 723,148.

To all whom it may concern:

Be it known that I, JOHN R. McCONNELL, a citizen of the United States, residing at Emmett, in the county of Canyon and State 5 of Idaho, have invented certain new and useful Improvements in Shock-Absorbers, of which the following is a specification, reference being had to the accompanying drawings.

10 This invention relates to new and useful improvements in shock absorbers and more particularly to a pneumatic device for counteracting the action of a vehicle spring to allow a gradual recoil thereof, and the primary 15 object of the invention is to provide a simple device of this character which will positively carry out the object for which the same is designed.

A further object of the invention resides 20 in providing a cylinder adapted to be mounted on the upper section of a spring or upon a portion of the frame, and a piston having connection with the axle of a vehicle whereby upon movement of the axle, the 25 piston will be operated within the cylinder.

Still another object of the invention resides in providing a device which is extremely simple and durable in construction, inexpensive to manufacture and one which 30 will be very efficient and useful in operation.

With these and other objects in view, the invention consists in the novel features of construction, combination and arrangement of parts as will be hereinafter referred 35 to and more particularly pointed out in the specification and claims.

In the accompanying drawing forming a part of this application, Figure 1 is a side elevation partly in section showing my improved device applied to use. Fig. 2 is a 40 front elevation thereof, and Fig. 3 is an enlarged vertical section through the cylinder.

In describing my invention, I shall refer 45 to the drawing in which similar reference characters designate corresponding parts throughout the several views and in which 1 indicates the axle of a vehicle of any desired type, preferably a motor vehicle upon 50 which is mounted in the usual manner, the full elliptic spring 2 and mounted on the end of the axle, in the usual manner, is the wheel 3.

My invention contemplates the provision 55 of a device to absorb the shock incident to the traveling of vehicles over rough roads

and also to provide a means whereby the recoil of the spring will be gradual and to this end, a cross bar 4 is secured through the medium of the bolts 5, to the upper section of the spring 2. Mounted on the cross bar 4, is a cylinder 6, the bottom of which is formed of a substantial drum or the like 7, the lower wall thereof being engaged with the bolts 5, whereby the complete cylinder 65 is secured to the cross bar. The wall of the cylinder 6 is provided, adjacent its lower end with a plurality of apertures 8 which extend throughout the periphery thereof, while the side wall of the drum 7 is also 70 provided with similar openings 9, which register with the aforesaid openings 8 and the top wall of said drum or the like 7, has an upwardly opening valve 10 seated therein. The stem or shank of this valve which 75 extends downwardly into the drum is encircled by a coil spring 11 which contacts with a nut 12 on the end of this shank and also contacts with the under face of the top wall of said drum, whereby said valve is 80 normally held in its closed position.

Slidably mounted in the cylinder 6, is a piston head 13, the rod 14 of which extends through the upper wall of the cylinder and connects with the horizontal portion of an 85 inverted U-shaped member 15. The arms of this member 15 extend downwardly along the sides of the cylinder 6 and are loosely disposed through openings 16 in the bar 4, the extreme free ends of said arms being 90 engaged with clamping bands 17 on the axle 1. From this construction, it will be seen that during the travel of a vehicle having my improved device applied thereto, should the wheels strike an obstruction or the like, 95 the axle 1 will, of course, be caused to rise upwardly compressing the spring 2 and simultaneously causing the piston 13 to rise in the cylinder 6. As the piston 13 is drawn upwardly, the valve 10 in the cylinder 100 will be opened and air drawn within the cylinder from the drum 7 and upon the recoil of the spring 2, the piston will be drawn downwardly to compress the air within the cylinder but, of course, this compression of the air will not permit the spring 105 to return with a sudden jar, but cause the same to return gradually and thereby not affect the occupants of the vehicle to any appreciable extent.

While I have shown full elliptic springs 110 in the drawings and have furthermore shown

the transverse bar 4, as being mounted on the upper sections of these springs, it will be understood that semi-elliptic or three-quarter elliptic springs may be used and the 5 bar 4 mounted directly on the frame of the vehicle.

From the foregoing it will be seen that I have provided a simple, inexpensive and efficient means for carrying out the objects 10 of the invention and while I have particularly described the elements best adapted to perform the functions set forth, it is obvious that various changes in form, proportion and in the minor details of construction 15 may be resorted to without departing from the spirit or sacrificing any of the principles of the invention.

Having thus described this invention, what I claim is:—

20 1. In a vehicle attachment, the combination with a yielding member, and an object supporting the same; of a cylinder mounted on said yielding member, the bottom of said cylinder being drum-like in design, the side 25 walls of said cylinder and the side walls of said drum being provided with registering apertures, and the top wall of said drum being provided with a valve seat, a valve mounted in said seat and designed to open 30 upwardly therefrom, spring means to nor-

mally retain said valve in its closed position, a piston disposed in said cylinder, and means carried by the aforesaid object for supporting said piston in position.

2. In a vehicle attachment, the combination with an axle, and a spring mounted thereon; of a bar rigidly secured to said spring, a cylinder mounted on said bar, the bottom of said cylinder being designed in the form of a drum, the walls of said drum 40 and the walls of said cylinder being provided with registering apertures, an upwardly opening valve mounted in the top wall of the drum, means to normally retain said valve in its closed position, a piston reciprocally mounted in said cylinder, the rod thereof extending through the upper wall of the cylinder, an inverted U-shaped member connected at its horizontal portion to the piston rod, the arms of said U-member being loosely disposed through said bar on opposite sides of said cylinder, and means to secure the free ends of said arms to the axle.

In testimony whereof I hereunto affix my 55 signature in the presence of two witnesses.

JOHN R. McCONNELL.
